Patented Aug. 25, 1959

185,967

SKATE GUARD

Stanley K. Johns, Quebec, Quebec, Canada, assignor to
St. Lawrence Manufacturing Co. Inc., Quebec, Quebec,
Canada, a company of Quebec

Application May 19, 1958, Serial No. 50,932

Term of patent 14 years

(Cl. D34—15)

The single figure is a perspective view of the skate guard.

The reverse side of the skate guard is substantially the same as that shown. The attachment spring is shown in dotted lines for the sake of convenience of illustration.

I claim:

The ornamental design for a skate guard, as shown and described.
